(57) **CLAIM**

The ornamental design for a game, as shown and described.

DESCRIPTION

FIG. 1 is a perspective view of the game comprising three stacked components.

FIG. 2 is a perspective view showing a first one of the three stacked components making up the game.

FIG. 3 is a perspective view showing a second one of the three stacked components making up the game; and,
FIG. 4 is a perspective view showing a third one of the three stacked components making up the game.

The design consists of the ornamental shape of a game comprising a plurality of stackable components. Each component is removable from the game, and has a symmetrical interior. The underside of each stackable component is not part of the design.
